UNITED STATES PATENT OFFICE

103,190

DESIGN FOR A CAKE OF SOAP

Sinclair G. Stanley, Chicago, Ill.

Application November 6, 1936, Serial No. 65,729

Term of patent 14 years

To all whom it may concern:

Be it known that I, Sinclair G. Stanley, a citizen of the United States, residing in Chicago, in the county of Cook and State of Illinois, have invented a new, original, and ornamental Design for a Cake of Soap, of which the following is a specification, reference being had to the accompanying drawing, forming a part thereof.

Fig. 1 is a top plan view of the cake of soap showing my design;

Fig. 2 is a side view of the same;
Fig. 3 is an end view of the same; and
Fig. 4 is an enlarged foreshortened perspective view of one of the elements of the same.

I claim:

The ornamental design for a cake of soap as shown and described.

SINCLAIR G. STANLEY.
